BOILER FEED PUMP CONTROL

Igor J. Karassik, South Orange, N. J., assignor to
 Worthington Pump and Machinery Corporation,
 Harrison, N. J., a corporation of Delaware

Application September 29, 1942, Serial No. 460,135

14 Claims. (Cl. 122—451)

This invention relates to the automatic control of boiler feed systems, and of centrifugal boiler feed pumps. More specifically, the invention contemplates the control of the temperature of the boiler feedwater entering a boiler feed pump, of the pressure of the feedwater at its point of entry into a boiler feed pump, or of both of the foregoing, for the purpose of maintaining a minimum difference between the pressure and the vapor pressure corresponding to the temperature of said entering feedwater for preventing flashing of the feedwater into steam with the resultant damage to the pumping system and interruption of the pumping action.

An object of the present invention is the provision of a mechanism and method of control which will provide an impulse when the margin or differential between the pressure of the feedwater entering the boiler feed pump and the vapor pressure corresponding to the temperature of such entering feedwater reaches a predetermined minimum at which flashing will successfully be avoided.

The impulse provided by the mechanism and method of control of the present invention may be utilized in several different manners to provide the result sought, depending upon the type of boiler feed system to which the invention is applied.

In systems wherein the pressure at the point of entry of the feedwater into the boiler feed pump is fixed or not subject to control, the present invention may be applied to provide an impulse which will effect the control of the temperature of the feedwater, and consequently the vapor pressure thereof, for maintaining the necessary differential between such vapor pressure and the pressure of the feedwater at its point of entry into the boiler feed pump for preventing flashing.

In so-called "closed" boiler feed cycles, the impulse provided by the application of the present invention may be used to control the pressure of the boiler feedwater, thereby maintaining the necessary minimum margin between such pressure and the vapor pressure corresponding to the temperature of the feedwater and preventing flashing of the feedwater.

In some systems, a combination of both of the above methods of control effected by the present invention may be employed, both methods being operated by the same impulse mechanism, as hereinafter described.

With these and other objects in view, as may appear from the accompanying specification, the invention consists of various features of construction and combination of parts, which will be first described in connection with the accompanying drawings, showing a boiler feed pump control of the preferred form embodying the invention, and

the features forming the invention will be specifically pointed out in the claims.

In the drawings:

Figure 1 is a diagrammatic drawing showing a control mechanism employing the features of the present invention.

Figure 2 is a diagrammatic drawing showing the application of the present invention to a boiler feed system.

Figure 3 is a diagrammatic drawing showing another form of control employing the features of the present invention.

Figure 4 is a diagrammatic drawing showing the present invention as applied to another type of boiler feed system.

Figure 5 is a diagrammatic drawing showing the present invention as applied to a "closed" boiler feed system embodying a variable speed boiler feed pump.

Referring more specifically to the drawings, in Figure 1 is shown an electrical type control mechanism A embodying the principles of the present invention. In this type of control, the instrument is actuated by the relative positions of two indicators, one of which converts temperature measurements into corresponding vapor pressure, while the other reads the actual pressure either at the point where the temperature measurement is taken or at the critical point where the differential between the vapor pressure and the absolute pressure of the feedwater is desired for preventing flashing.

Temperature or pressure changes which would reduce the margin between the absolute pressure of the feedwater and the vapor pressure below the predetermined minimum actuate the control mechanism and open or close contacts or relays in the electrical control circuit. This control is made up of two separate pieces of mechanism, the first of which is used to measure pressure differences, and the other to translate these differences into the motions required to open or close certain control valves or otherwise effect changes in the boiler feed system for controlling the absolute pressure or the temperature of the feedwater, as will be hereinafter described in connection with the application of the mechanism.

In Figure 1, a temperature sensitive bulb 1 is used to measure the temperature at the point desired, transmitting variations of internal pressure due to temperature changes through the capillary tubing 2 and a specially constructed and calibrated bellows 3 to a movable indicating pointer 4. This is accomplished by filling the bulb 1 with a liquid or gas so arranged that the temperature changes at the bulb cause changes in the internal fluid corresponding to changes in the pressure at which the feedwater would vaporize corresponding to its temperature. The bellows 3 is so calibrated that the attached pointer 4

moves along an indicating scale 5 which reads the vapor pressure corresponding to the temperature directly in p. s. i. A further feature of the pointer travel is that the amount of travel per unit of pressure change is independent of the absolute value of the actual vapor pressure measured.

A similar pointer 6 is connected to the absolute pressure measuring device 7 and possesses the same features with respect to travel per unit of pressure change. This device 7 includes a bellows 8 connected by tubing 9 to the point where the pressure measurement is taken, or to the critical point where the margin of difference is required.

The distance along the scale 5 between the two pointers 4 and 6 represents, at all temperatures and pressures, the net difference between the vapor pressure corresponding to the temperature of the feedwater at the critical point and the absolute pressure at such point.

An extension arm 4a is attached to the vapor pressure indicating pointer 4, the length of which represents the minimum permissible pressure differential between the absolute pressure available and the vapor pressure. An electrical circuit 10 is established, with individual connections 11 and 12 to each of the two pointers 4 and 6, respectively. So long as the available pressure difference remains in excess of the predetermined minimum differential, the electrical circuit will remain open, but upon lowering of the pressure difference to the minimum permissible, as predetermined by the length of the arm or extension 4a, this extension will contact the pointer 6 and close the electrical circuit 10. In effect, the mechanism would perform the function of a switch actuated by the difference between absolute pressure and vapor pressure.

It is to be understood that the above is only one of several possible applications of the principle of the present invention and that other constructions are possible to provide the desired result, without departing from the spirit of the present invention.

The opening and closing of the electrical circuit 10 may be employed for actuating a solenoid operated or motor driven modulating valve of any approved type which may be purchased upon the market and which may be used as a pilot valve or a proportioning valve to control the feedwater system. In Figure 1, the valve structure 13 is shown as a solenoid operated valve, of any desired type which may be purchased upon the market, and some applications of this control as disclosed in Figure 1 will be described herein-after. If desired, the valve 13 may be dispensed with and the controlled electrical circuit employed to effect the control of the boiler feed system, depending upon the type of system in which it is employed.

In Figure 2 is illustrated diagrammatically a boiler feed system wherein the boiler feed pump 21 takes its suction from a direct contact feedwater heater 22 through the main feed suction line 24. This line 24 carries the feedwater at a temperature T_1 , which has a corresponding vapor pressure P_{V_1} . The pressure at the suction 25 of the boiler feed pump is P_3 . An auxiliary feed line or bypass 26 is provided, leading directly from the discharge of the condensate pump 27 into the main feed line 24 beyond the feedwater heater 22, providing a bypass around the feedwater heater 22. The temperature of the feedwater in this auxiliary line 26 is T_2 and is lower than that in the line 24 beyond the feedwater heater 22. A

valve 28 is interposed in this bypass line 26 for controlling the flow of feedwater through this line 26.

This valve 28 is shown in Figure 2 as a solenoid operated valve of any approved construction, controlled by a control mechanism A such as is illustrated in Figure 1. It is to be understood however that the mechanism illustrated in Figure 3 could also be utilized for the purpose in this system.

If Q_1 is the flow through the main suction line 24, Q_2 the flow through the auxiliary line or bypass 26, and Q_3 the sum of Q_1 and Q_2 (or the total flow to the boiler feed pump), the temperature T_3 of the mixture is represented approximately by the following equation:

$$(1) \quad T_3 = \frac{Q_1 \times T_1 + Q_2 \times T_2}{Q_3}$$

and P_{V_3} , the vapor pressure of the feedwater at the temperature T_3 can thus be controlled by the position of the valve 28, through increasing or decreasing the flow Q_2 through the auxiliary line or bypass 26. When employing the mechanism illustrated in Figure 1, this flow is not proportionately controlled but when employing the structure shown in Figure 3, the control is proportionate.

The prime requisite of the arrangement is to maintain a given minimum excess of pressure at the boiler feed pump suction over the vapor pressure P_{V_3} . In other words, to maintain the following relation:

$$(2) \quad P_3 \geq P_{V_3} \text{ plus a constant}$$

Under normal conditions, this relationship will prevail automatically since the pressure P_3 is the sum of the pressure in the heater and of the static submergence, while the pressure in the heater is equivalent to the vapor pressure therein. However, the steam supply to the direct contact heater comes generally from an extraction stage of the main turbine and when the electrical load undergoes a sudden drop, this latter is accompanied by a sudden drop in steam pressure at the heater without a corresponding temperature drop at the pump suction. A safety factor must therefore be provided to take care of the time lag which exists between a sudden reduction of pressure in the heater and the ultimate reduction of temperature at the pump suction.

It would be possible to install both a thermometer calibrated to read directly the vapor pressure corresponding to the temperature T_3 and a pressure gauge at the pump suction for reading the pressure P_3 . The position of the valve could then be varied manually in such manner as to fulfill the requirements of the equation (2) above. This however would be both tedious and impractical and the object of the present invention is to provide such a result automatically.

In other words, when the difference between the vapor pressure at the critical point 25 and the absolute pressure at the critical point 25 falls below the desirable minimum, the extension contact arm 4a of the control mechanism A will engage the pointer 6 and close the electrical circuit 10 through the solenoid valve structure 13, opening the valve 28 to permit a predetermined quantity of feedwater to flow from the condensate pump 27 directly to the boiler feed pump 21, bypassing the feedwater heater 22 and consequently lowering the temperature of the feedwater at the critical point, or at the suction of the boiler feed pump 21, raising the pressure dif-

ferential between the vapor pressure and the absolute pressure and preventing flashing of the boiler feedwater in the boiler feed pump.

In Figure 3 of the drawings a spring-loaded diaphragm type valve is employed for obtaining the same control as provided by the mechanism shown in Figure 1. In this structure the stem 15 of the valve 14 is connected at its upper end to a diaphragm 16. The chamber 16a on one side of the diaphragm 16 is subjected to the absolute pressure of the feedwater at the critical point by means of the tubing 17, while the chamber 16b on the other side of the diaphragm 16 is subjected to a pressure corresponding to the vapor pressure at the temperature being measured by means of a temperature sensitive bulb 19 located at such critical point and connected to the diaphragm casing by the capillary tubing 18. This bulb 19 is similar to the bulb 1 employed in the structure shown in Figure 1 of the drawings.

A loading spring 20 is provided which exerts a constant pressure upon the diaphragm 16 in opposition to the absolute pressure exerted thereon. The tension or compression of this spring 20 is determined in accordance with the desired minimum pressure differential or margin. When the vapor pressure rises to a point where it, plus the pressure exerted by the spring 20, is greater than the opposed absolute pressure, the valve 16 will open. When the sum of the vapor pressure plus the constant pressure as exerted by the spring 20 is less than the absolute pressure, the valve will close. In fact, as the sum of the vapor pressure and the constant pressure of the spring approaches the absolute pressure, through the gradual rising of the vapor pressure due to the increase in temperature, the valve will begin to open, and a proportioning effect is thus provided. It will be seen that the valve will be opened only when the difference between the vapor pressure and the absolute pressure is less than the predetermined minimum, as represented by the constant pressure of the spring 20. This type of mechanism is especially suitable for use as a proportioning valve to be employed in systems where such type of control is adaptable.

In Figure 4 is illustrated a boiler feed system wherein the feedwater is drawn from a direct contact feedwater heater 30 through a suitable line 30a by the suction of the multi-stage boiler feed pump 31, and is then withdrawn from an intermediate stage of the boiler feed pump through the line 32, heated in a closed feedwater heater 33, and returned to a following stage of the pump 31 through the line 34.

In this type of system there is always available feedwater at a temperature lower than that prevailing at the given point of reentry of the feedwater into the boiler feed pump. The impulse provided by the control of the present invention is thus used to control the admission of such colder feedwater through an auxiliary feed line, the final temperature of the resulting mixture being reduced sufficiently to permit satisfactory operation of the boiler feed pump.

In this system shown in Figure 4 an auxiliary pipe or bypass 35 is provided between the discharge pipe 32 from an intermediate stage of the boiler feed pump 31 to the feedwater heater 33 and the return pipe 34 to a succeeding stage of the boiler feed pump 31. A diaphragm operated valve 14 of the type shown in Figure 2 of the drawings is located in this pipe or bypass 35. Tubing 18 connects the chamber 16b on one side

of the diaphragm 16 to a temperature sensitive bulb located in the return pipe 34, while tubing 17 connects the chamber 16a on the other side of the diaphragm 16 to the boiler feed pump 31 at a lower stage. Generally the pressure at the intermediate stage of the boiler feed pump from which the feedwater is withdrawn for heating is sufficiently greater than the vapor pressure corresponding to its return temperature, and the application of the control mechanism here is not for the purpose of establishing a relationship between these two pressures. However, through the design of the boiler feed pump 31, some of the feedwater returning may be permitted to leak into a lower stage of the pump, the pressure of which may fall below the vapor pressure corresponding to the temperature of such returning feedwater. The control is employed to prevent this possibility.

In the event that the pressure in the lower stage of the pump 31 to which the tubing 17 is connected falls below the vapor pressure corresponding to the temperature of the feedwater being returned to the pump 31 through the line or pipe 34, the decrease in such pressure will cause movement of the diaphragm 16 to open the valve 14 and allow bypassing of the feedwater around the feedwater heater 33 directly to the stage of the boiler feed pump 31 to which the feedwater returns from the feedwater heater 33, thus lowering the temperature in this stage of the pump to prevent flashing, and reestablishing the desired pressure differential, which will in turn cause operation of the diaphragm 16 to close the valve 14.

In both of the systems just described and illustrated in Figures 2 and 4 the principle of the present invention is employed for controlling the temperature of the feedwater for maintaining the required differential. In Figure 5 of the drawings the principle of the present invention is applied for controlling the absolute pressure of the feedwater, but for accomplishing the same result, i. e. the maintenance of the minimum differential between the absolute pressure and the vapor pressure corresponding to the temperature of the feedwater to prevent flashing in the boiler feed pump.

In the system shown in Figure 5 the use of the impulse of the present invention to control the pressure at the point of entry of the feedwater into the boiler feed pump is shown in a so-called "closed" feed cycle, wherein several feed pumps are operated in series with closed feedwater heaters interposed between successive pumps, one or more of such pumps being operated at variable speed. Normally the variable speed operation is restricted to the low pressure unit in such a system, the controlling factor being the total flow to the boiler and the controlling mechanism either an excess pressure or a constant pressure regulator, which is used to vary the speed of the centrifugal pump, which may be driven by a steam turbine, a variable speed electric motor, or by a constant speed prime mover through a variable speed coupling.

Such means of control is obviously unaffected by the relationship between the temperature and the pressure at the suction of any one of the pumps, and conditions might arise where the speed regulation lowers the suction pressure of any given pump dangerously close to or even below the vapor pressure at the suction of such pump.

The system shown in Figure 5 includes a con-

stant speed condensate pump 40, followed by a closed feedwater heater 41, a variable speed primary boiler feed pump 42, another closed feedwater heater 43, and finally a constant speed secondary boiler feed pump 44, whose discharge leads to the boiler 45 through the piping 48.

It is obvious that the margin between the pressure at the suction of the secondary pump 44 and the vapor pressure corresponding to the temperature of the feedwater entering the pump 44 must never be allowed to fall below a certain predetermined value, which depends on the pump design, else flashing would occur, disrupting the operation of the pump and of the system. Thus, while normally the speed of the primary boiler feed pump 42 may be left under the control of the excess pressure or constant pressure regulator 46, the electrical type control mechanism shown in Figure 1 and indicated at A should be employed to set a definite limit to the speed reduction so occasioned. This limit, as provided by the control mechanism A, will of course be variable, depending entirely upon the interrelation between the pressure of the feedwater at the suction of the pump 44 and the vapor pressure corresponding to the temperature of the feedwater at that point, as measured by and acted upon by the control mechanism A.

The excess pressure regulator 46 may be of any suitable type such as may be purchased upon the open market for providing regulation of the speed of the electric motor 49 which drives the pump 42, as for example the Copes electric pump control sold by the Northern Equipment Co. of Erie, Pa. The regulator indicated at 46 embodies a rheostat, the operation of which is controlled by a mechanism connected to and controlled by the pressure in the boiler feedwater line 48 and the steam pressure in the line 50 to the main turbine for maintaining an excess of boiler feed pressure over the steam pressure. Upon an increase in available excess feedwater pressure over boiler pressure due to operating conditions or load, the regulator 46 would act to reduce the speed of the pump motor 49 and the boiler feed pump 42, reducing the pressure in the line 48 and boiler 45. This would likewise reduce the pressure at the suction of the constant speed boiler feed pump 44. Such a reduction would not necessarily be accompanied by a companion drop in temperature at that point, so that the differential between the vapor pressure and the absolute pressure might become so small as to cause flashing.

To prevent this, a control mechanism A such as shown in Figure 1 is introduced for limiting the reduction in speed of the pump 42 by the regulator 46. The control mechanism A of the present invention may be adapted to provide such a result in any of a number of manners, only one of which is shown, by way of illustration. The application of the control in any definite installation will depend upon the apparatus employed and other factors.

In Figure 5 the control mechanism A is employed for operation of a three-way solenoid operated pilot valve 51 of any approved form. The electrical circuit 10, opened and closed by the operation of the control mechanism A under the influence of the differences in the absolute and vapor pressure at the suction of the pump 44, is connected to the solenoid 54 for energizing and deenergizing it. A drop in the absolute pressure to a point sufficiently near the vapor pressure, depending upon the setting of the control mech-

anism A, will actuate the control mechanism A to close the circuit 10, energizing the solenoid 54 and opening the three-way valve 51 to allow pressure fluid, from any suitable source (not shown), to be fed through the piping 55 into the cylinder 56, moving a piston 57 and rod 58 to the right against the arm 59 of the rheostat embodied in the regulator 46, and moving such arm 59 to the right, increasing the speed of the motor 49 and pump 42, or in other words, limiting the reduction in motor speed. The result is an increase in pressure of the boiler feedwater at the suction of the pump 44, thus avoiding the danger of flashing. The increase in absolute pressure, reacting on the control mechanism A, actuates the control and opens the circuit 10, deenergizing the solenoid 54 and cutting off the flow of pressure fluid through the valve 51 to the cylinder 56. The pressure fluid in the cylinder 56 will then bleed back through the three-way valve 51 to atmosphere, releasing the pressure of the rod 58 against the arm 59 of the rheostat and allowing the excess pressure regulator 46 to resume control over the speed of the motor and pump 42.

Thus it will be seen that the limitation upon the reduction in speed caused by the excess or constant pressure regulator 46 is a variable one, created by the reaction of the control mechanism of the present invention, which provides an impulse at any time that the vapor pressure and the absolute pressure at the critical point approach within a predetermined distance of each other.

It is to be understood that the system as illustrated in Figure 5 could be controlled in either of the two manners illustrated in Figures 3 and 4, as by placing a bypass about the heater 43 in which a valve controlled by either of the mechanisms illustrated in Figures 1 and 2 is inserted. Such construction could be employed in lieu of that just described, or even in conjunction therewith, as an added safety factor.

It will be understood that the invention is not to be limited to the specific construction or arrangement of parts shown, but that they may be widely modified within the invention defined by the claims.

What is claimed is:

1. The method of controlling the relationship between the absolute pressure and the vapor pressure corresponding to the temperature of the feedwater in a boiler feed system including a boiler feed pump and a feedwater heater to prevent flashing of feedwater into vapor in the boiler feed pump which includes controlling the temperature of the feedwater in advance of the suction of the boiler feed pump to insure at least a predetermined differential between the absolute pressure in the boiler feed system and the vapor pressure corresponding to the temperature of the feedwater by bypassing the feedwater around the feedwater heater in the boiler feed system and into the suction of the boiler feed pump when the vapor pressure corresponding to the temperature of the feedwater reaches a predetermined point approaching the existing absolute pressure of the feedwater at a predetermined point in the boiler feed system.

2. In a boiler feed system embodying a boiler, a boiler feed pump and a feedwater heater, means for maintaining a minimum differential between the absolute pressure at a predetermined point in the system in advance of the suction of the boiler feed pump and the vapor pressure corresponding to the feedwater temperature at

a predetermined point in the system in advance of the suction of the boiler feed pump to prevent the flashing of feedwater into vapor in the boiler feed pump, including means actuated by the temperature of the feedwater at said temperature predetermined point, means actuated by the pressure at said pressure predetermined point, and means actuated upon a predetermined degree of actuation of said temperature actuated means and said pressure actuated means for maintaining said minimum differential between said pressures.

3. In a boiler feed system embodying a boiler, a boiler feed pump and a feedwater heater, means for maintaining a minimum differential between the absolute pressure at a predetermined point in the system in advance of the suction of the boiler feed pump and the vapor pressure corresponding to the feedwater temperature at a predetermined point in the system in advance of the suction of the boiler feed pump to prevent the flashing of feedwater into vapor in the boiler feed pump, including means actuated by the temperature of the feedwater at said temperature predetermined point, means actuated by the pressure at said pressure predetermined point, and means actuated upon a predetermined degree of actuation of said temperature actuated means and said pressure actuated means for limiting the temperature of the feedwater in the system to maintain said minimum differential between said absolute pressure and the vapor pressure corresponding to said temperature.

4. In a boiler feed system embodying a boiler feed pump, a feedwater heater and a boiler, a control for maintaining a minimum differential between the absolute pressure at a predetermined point in the boiler feed system in advance of the suction of the boiler feed pump and the vapor pressure corresponding to the temperature of the feedwater at a predetermined point in the system in advance of the suction of the boiler feed pump, embodying means actuated by the temperature at said temperature predetermined point for indicating the vapor pressure corresponding to said temperature, means for indicating the pressure at said pressure predetermined point, means operated by said pressure indicating means and said temperature actuated vapor pressure indicating means for creating an impulse when the difference between the two indicated pressures reaches a predetermined minimum, and means actuated by said created impulse to vary the temperature of said feedwater and increase the differential between the two pressures.

5. In a boiler feed system embodying a boiler feed pump, a feedwater heater and a boiler, a control for maintaining a minimum differential between the absolute pressure at a predetermined point in the boiler feed system in advance of the suction of the boiler feed pump and the vapor pressure corresponding to the temperature of the feedwater at a predetermined point in the system in advance of the suction of the boiler feed pump, embodying means actuated by the temperature at said temperature predetermined point for indicating the vapor pressure corresponding to said temperature, means for indicating the pressure at said pressure predetermined point, means operated by said pressure indicating means and said temperature actuated vapor pressure indicating means for creating an impulse when the difference between the two indicated pressures reaches a predetermined minimum, and means

actuated by said created impulse to increase the differential between the two pressures.

6. In a boiler feed system embodying a boiler feed pump and a feedwater heater, means for maintaining a predetermined minimum differential between the absolute pressure at a predetermined point in the boiler feed system in advance of the suction of the boiler feed pump and the vapor pressure corresponding to the temperature of the feedwater at said predetermined point to prevent flashing of the feedwater into vapor in the boiler feed pump, comprising means for determining the pressure at said predetermined point, means for determining the vapor pressure corresponding to the temperature at said predetermined point, an operating member subject to said absolute pressure at said predetermined point and to said vapor pressure at said predetermined point in opposed relation to each other, said member operable when the said pressures vary to within the predetermined minimum differential to increase the differential between said pressures beyond said predetermined minimum.

7. In a boiler feed system embodying a boiler feed pump and a feedwater heater, means for maintaining a predetermined minimum differential between the absolute pressure at a predetermined point in the boiler feed system in advance of the suction of the boiler feed pump and the vapor pressure corresponding to the temperature of the feedwater at said predetermined point to prevent flashing of the feedwater into vapor in the boiler feed pump, comprising means for determining the pressure at said predetermined point, means for determining the vapor pressure corresponding to the temperature at said predetermined point, an operating member subject to said absolute pressure at said predetermined point and to said vapor pressure at said point in opposed relation to each other, said member operable when the said pressures vary to within the predetermined minimum differential to vary the temperature of the feedwater for increasing the differential between said pressures beyond said predetermined minimum.

8. In a boiler feed system embodying a boiler, a boiler feed pump and a feedwater heater, means for maintaining a minimum differential between the absolute pressure at a predetermined point in the system in advance of the suction of the boiler feed pump and the vapor pressure corresponding to the feedwater temperature at a predetermined point in the system in advance of the suction of the boiler feed pump to prevent the flashing of feedwater into vapor in the boiler feed pump comprising, a temperature sensitive bulb inserted in the feedwater flow at said temperature predetermined point and having an internal pressure proportional to the vapor pressure corresponding to the feedwater temperature, a pressure actuated device responsive to variation of pressure within said bulb occasioned by variation in temperature of the feedwater, a pressure actuated device responsive to variations in absolute pressure in the system at said pressure predetermined point, an electric circuit, means carried by said pressure actuated devices for opening and closing said electric circuit when their relative movement responsive to the variations in absolute pressure and temperature is within certain predetermined limits, a solenoid operated valve in the system, said electrical circuit energizing and deenergizing said solenoid operated valve for bypassing feedwater around said feedwater heater and thereby varying the

temperature of the feedwater to increase the differential between the absolute pressure and the vapor pressure corresponding to the temperature of the feedwater beyond the predetermined minimum.

9. In a boiler feed system embodying a boiler, a variable speed feed pump, a constant speed feed pump, and a feedwater heater; means for maintaining a minimum differential between the absolute pressure at a predetermined point in the system in advance of the suction of the constant speed boiler feed pump and the vapor pressure corresponding to the feedwater temperature at a predetermined point in the system in advance of the suction of the constant speed boiler feed pump to prevent the flashing of feedwater into vapor in the constant speed boiler feed pump comprising, a temperature sensitive bulb inserted in the feedwater flow at said temperature predetermined point and having an internal pressure proportional to the vapor pressure corresponding to the feedwater temperature, a pressure actuated device responsive to variation of pressure within said bulb occasioned by variation in temperature of the feedwater, a pressure actuated device responsive to variations in absolute pressure in the system at said pressure predetermined point, an electric circuit, means carried by said pressure actuated devices for opening and closing said electric circuit when their relative movement caused by the variations in absolute pressure and temperature is within certain predetermined limits, and means actuated by closing of said electric circuit for increasing the speed of the variable capacity feed pump to vary the absolute pressure in the system for increasing the differential between the absolute pressure and the vapor pressure corresponding to the temperature of the feedwater at the predetermined point beyond the predetermined minimum.

10. In a boiler feed system embodying a boiler feed pump and a feedwater heater, means for maintaining a predetermined minimum differential between the absolute pressure at a predetermined point in the boiler feed system in advance of the suction of the boiler feed pump and the vapor pressure corresponding to the temperature of the feedwater at said predetermined point to prevent flashing of the feedwater into vapor in the boiler feed pump, comprising means for determining the pressure at said predetermined point, means for determining the vapor pressure corresponding to the temperature of the feedwater at said predetermined point, an operating member subject to the absolute pressure at said predetermined point and to the vapor pressure at said point in opposed relation to each other, a bypass for bypassing water around said feedwater heater to said boiler feed pump, a valve in said bypass controlled by said operating member, said member operable when the difference between said absolute pressure and said vapor pressure is less than the predetermined minimum to open said valve and bypass feedwater about said feedwater heater for varying the temperature of the feedwater and thereby the corresponding vapor pressure at said predetermined point and increasing the differential between said pressures at said point.

11. In a boiler feed system embodying a constant speed feed pump and a variable speed boiler feed pump and a feedwater heater, means

for maintaining a predetermined minimum differential between the absolute pressure at a predetermined point in the boiler feed system in advance of the suction of the boiler feed pump and the vapor pressure corresponding to the temperature of the feedwater at said point to prevent flashing of the feedwater into vapor in the constant speed boiler feed pump, comprising, means for determining the pressure at said predetermined point, means for determining the vapor pressure corresponding to the temperature at said predetermined point, an operating member subject to said absolute pressure at said predetermined point and to said vapor pressure at said point in opposed relation to each other, a speed regulator for controlling the speed of said variable speed boiler feed pump, said operating member operable when the difference between the absolute pressure and the vapor pressure becomes less than said predetermined minimum to actuate said regulator for increasing the speed of said variable speed boiler feed pump and thereby increase the differential between said pressures beyond said predetermined minimum.

12. The method of controlling the relationship between the absolute pressure and the vapor pressure corresponding to the temperature of the feedwater in a boiler feed system wherein the feedwater is heated and including a boiler feed pump to prevent flashing of feedwater into vapor in the boiler feed pump which includes limiting the temperature of the feedwater in advance of the boiler feed pump to insure at least a predetermined differential between the absolute pressure in the boiler feed system and the vapor pressure corresponding to the temperature of the feedwater.

13. The method of controlling the relationship between the absolute pressure and the vapor pressure corresponding to the temperature of the water in a boiler feed system wherein the feedwater is heated and which includes a boiler feed pump to prevent flashing of the feedwater into vapor in the boiler feed pump which includes limiting the absolute pressure in the boiler feed system in advance of the boiler feed pump to insure at least a predetermined differential between the absolute pressure in the boiler feed system and the vapor pressure corresponding to the temperature of the feedwater.

14. The method of controlling the relationship between the absolute pressure and the vapor pressure corresponding to the temperature of the feedwater in a boiler feed system including a variable speed feed pump and a constant speed feed pump together with a feedwater heater to prevent flashing of feedwater into vapor in the constant speed pump, which includes controlling the absolute pressure in the boiler feed system in advance of the suction of the constant speed boiler feed pump for maintaining a predetermined differential between the absolute pressure in the boiler feed system and the vapor pressure corresponding to the temperature of the feedwater in the system by increasing the speed of the variable speed feed pump to increase the absolute pressure when such absolute pressure falls to a predetermined degree above the vapor pressure corresponding to the temperature of the feedwater at a predetermined point in the boiler feed system.
